Patented Mar. 18, 1919.

UNITED STATES PATENT OFFICE.

THOMAS A. CHALMERS, OF CAMDEN, NEW JERSEY.

STEAM-TRAP.

1,297,659.

Specification of Letters Patent. Patented Mar. 18, 1919.

Application filed July 18, 1918. Serial No. 245,549.

To all whom it may concern:

Be it known that I, THOMAS A. CHALMERS, a citizen of the United States, and a resident of Camden, county of Camden, State of New Jersey, have invented certain Improvements 5 in Steam-Traps, of which the following is a specification.

My invention relates to certain improvements in steam traps particularly adapted 10 for removing the water of condensation from the drying cylinders of drying machines, but it will be understood that the invention can be used in connection with other machines where a large quantity of water accumulates 15 and which must be removed in order to produce the best results.

The object of my invention is to improve the construction of such a trap, and to provide a reservoir from which the float box can 20 be quickly filled and also to provide a trap which can be readily operated so as to relieve the cylinder of the water of condensation.

In the accompanying drawings:—

25 Figure 1, is a vertical sectional view illustrating my improved trap, the valve being in the closed position;

Fig. 2, is a plan view; and

30 Fig. 3, is a detached sectional view, showing the main valve in the open position.

1 is a casing inclosing a chamber 10 in which the mechanism is mounted. 2 is a cover for the casing, secured thereto in any suitable manner. 3 is the inlet pipe leading 35 from the cylinders to a drying machine, or other apparatus in which the water of condensation accumulates. Located in the cover, in the present instance, is a passage 5, which communicates with the pipe 3 and with the 40 interior of the main valve casing 6. Mounted on the cover 2 is a reservoir 7 connected by a neck 8 with the chamber 10. A pipe 9 also forms communication between the bottom of the reservoir 7 and the chamber and 45 has a check valve 11 closing against pressure from the interior of the casing.

12 is a pipe leading from the upper end of the chamber 10 to the upper portion of the reservoir 7 and has a check valve 13 therein, closing 50 against pressure from the chamber. In the chamber 10 is a float box 14 which is hollow and is open at the top. At the center of the box is a tube 15 forming an opening for the passage of the stem 16 of the valve 17. 55 In the present instance, this valve stem has a pin 18 which extends into a slot 19 in the

tube 15 so as to allow the float box to have a certain amount of vertical movement without operating the stem of the valve. The valve 17 is a balanced valve having two beveled 60 disks 20 adapted to seats 21 in the casing 6.

The stem 16 extends from the screw cap 22 in the lower portion of the valve casing 6 and also extends through a projection 23 forming part of the casing. In the casing is 65 a passage 24 forming communication with the space below the lower disk and this passage is open to the interior of the chamber 10, as well as the passage 25, which is above the valve, so that the moment the valve is 70 open the water of condensation in the valve casing 6, in the passage 5, and the pipe 3 will flow through the valve casing and into the chamber 10.

26 is a pipe screwed into the bottom of the 75 neck 8 of the reservoir 7, and extends into the float box, terminating at a point near the bottom, as shown in Fig. 1. A pipe 27 forms a continuation of the pipe 26 and extends to a point above the bottom of the outlet pipe 80 28 from the reservoir which leads to waste.

When the parts are in the position illustrated in Fig. 1, the valve 17 is closed against its seat and the water of condensation accumulates in the casing 6, connection 85 5 and pipe 3. There is water in the reservoir, as indicated in the drawings, the surplus water having escaped through the outlet pipe 28. The water in the reservoir 7 flows through the pipe 9 past the check valve 11 90 and into the float box 14, and as the water accumulates in the float box it tends to settle the float box in the water in the chamber 10 until the box sinks by its own weight. The first movement of the box will not affect the 95 stem 16, owing to the lost motion between the pin 18 and the ends of the slot 19 in the tube 15 of the box, but as soon as this lost motion is taken up the box will move the valve 17 off its seat in the casing 6 and the 100 main body of water of condensation will flow from the passage 5 into and through the casing 6, past the valve 17, through passages 24 and 25 and into the chamber 10. The water flowing into the chamber 10 and float box 105 14 will be forced, by the steam back of the water, through the pipes 26 and 27 and into the reservoir 7, and as the water accumulates in this reservoir it will flow out through the pipe 28 to waste.

As soon as a certain 110 amount of water is discharged, the float box will rise, owing to its buoyancy, and will

close the valve 17 against its seat. When the valve 17 is opened, the first inrush of water causes air to be forced out of the chamber 10, through the pipe 12 and past the check valve 13, as the pressure is not sufficient to close the valve, and a certain amount of water is carried with this air and is discharged into the reservoir 7.

It will be seen from the above construction, that I am enabled to have a continuously acting steam trap which will work automatically to draw off the water of condensation from machines where a considerable amount of steam is condensed, such as the cylinders of a drying machine, and the water in the reservoir will flow down into the float box and will cause the float box to be dropped so as to open the main valve, and the inrush of water, caused by the pressure of steam back of it, will flow into the chamber 10 and will pass up into the reservoir and will flow to waste. As soon as the pressure is relieved the main valve will again close and the water in the reservoir, which has accumulated below the waste pipe, will flow through the pipe 10 again into the float box and the operation will be repeated so that there will be a constant movement of the box to relieve the cylinders of the water of condensation.

I claim:—

1. The combination in a steam trap, of a casing inclosing a chamber; a float box mounted in the chamber; a supply pipe for the water of condensation; a main valve closing the supply pipe, said main valve being opened when sufficient water accumulates in the float box; a reservoir; a passage leading from the reservoir to the chamber; and a pipe extending from a point near the bottom of the float box to the reservoir, so that when water is forced into the chamber by the pressure of the steam when the main valve is opened, it will be forced into the reservoir from the float box and the float box will rise, closing the main valve.

Copies of this patent may be obtained for five cents each, by addressing the "Commissioner of Patents, Washington, D. C."

2. The combination in a steam trap, of a casing inclosing a chamber; a float box therein; a supply pipe through which the water of condensation flows; a valve casing 50 communicating with said pipe; a main valve in said casing actuated on the movement of the float box; a reservoir above the chamber; a pipe extending from a point near the bottom of the float box to the reservoir; a pipe leading from the reservoir into the chamber; a check valve in said pipe; an air escape pipe communicating with the reservoir and having a check valve; and a waste pipe leading from the upper portion of the reservoir. 60

3. The combination in a trap for water of condensation, of a casing having a chamber; a passage communicating with the chamber and terminating in a valve casing; a balanced valve in said casing; a float box 65 mounted in the chamber, said valve having a stem arranged to be engaged by the float box to open the valve when the box sinks by the accumulation of water in the box; and a discharge pipe extending into the float 70 box.

4. The combination of a casing, a float box therein; a valved inlet for water of condensation and arranged to discharge into the float box; a reservoir above the casing; 75 a pipe forming a communication between the float box and the reservoir; and a pipe leading from the reservoir and arranged to discharge water from the reservoir into the float box to open the valve.

5. The combination of a casing; a float box therein; a valved inlet for water of condensation; a reservoir; an outlet for the reservoir some distance above its bottom; 85 a pipe leading from a point near the bottom of the float box to a point above the bottom of the outlet pipe from the reservoir; and means for supplying the float box with water from the reservoir.

In witness whereof I affix my signature. 90

THOMAS A. CHALMERS.
